UNITED STATES PATENT OFFICE.

ARTHUR L. BETTS AND ANTHONY B. FEY, OF CINCINNATI, OHIO, ASSIGNEES TO
AUGUSTINE DAVIS, JR., OF COVINGTON, KENTUCKY.

BUCKET BOX.

Application filed November 16, 1922. Serial No. 601,234.

To all whom it may concern:

Be it known that we, ARTHUR L. BETTS and ANTHONY B. FEY, citizens of the United States, residing at Cincinnati, in the county of Hamilton and State of Ohio, have invented certain new and useful Improvements in Bucket Boxes, of which the following is a specification.

The invention has to do with welded truck tanks such as are used for carrying and vending gasoline and oil. An important element of these vehicles is the bucket-box provided at the rear end of the horizontal tank for holding the buckets, funnels, etc., forming part of the equipment. The object of this invention is to produce a stronger and better appearing bucket-box than heretofore, and one capable of advantageous manufacture. In Patent No. 1,248,088 dated Nov. 27, 1917, to Augustine Davis, Jr., has been disclosed an attached bucket-box, welded onto the tank so as to form a unit therewith, and the present object is to improve the connection between the tank extension and the box, securing a strong and tight connection in a simple and advantageous manner, as well as to improve the construction of the bucket-box itself. Other objects and features of the invention will become apparent as the specification proceeds.

In the accompanying drawings forming a part hereof:

Fig. 1 is a rear elevation of a bucket-box construction in accordance with the invention, a lower corner portion of the walls being shown broken away to illustrate parts in section;

Fig. 2 is a rear elevation of the bucket-box without doors and lining showing the lugs bent rearward from the back sheet for attachment to the extension of the tank;

Fig. 3 is an enlarged vertical section on the line 3-3 of Fig. 1;

Fig. 4 is an enlarged fragmentary horizontal section on the line 4-4 of Fig. 1;

Fig. 5 is an enlarged fragmentary section on the line 5-5 of Fig. 2;

Fig. 6 is an elevation of the rear sheet section or blank with the side wings and top extensions preparatory to bending, the large interior opening being shown cut out of the back and cuts formed in the margin of said opening to form the attaching lugs, which have not been bent out of the plane of the sheet in this view;

Fig. 7 is an elevation of the three-piece top front section with its parts united but unbent;

Fig. 8 is a plan view of the bottom sheet section prior to bending; and

Fig. 9 is an elevation of a form of two-piece back sheet section with side wings and top extensions intended for a bucket-box in which the upper section of the box conforms to the outline of the tank, the dotted line indicating the outline of the tank.

The rear portion of the shell of the tank is marked 1, and the rear head 2. The head, as is customary, is inserted into the shell, somewhat inwardly of the rear end thereof, and is formed with a rearwardly directed peripheral flange 3, which is autogenously welded to the inner face of the shell as indicated at 4. The shell projects for a short distance beyond this flange and weld, forming an extension 5, to which the bucket-box 6 is autogenously united.

The body or case of the bucket-box is constructed of comparatively heavy sheet metal fabricated in certain sections, which are joined by autogenous welds produced with a suitable welding torch or electrically. One of the sections is a back sheet section 7 having an upwardly curved top edge 8, and side wings 9 with upward extensions 10.

The side wings are bent forward on the vertical lines 11, to form the sides of the box, and the extensions 10 are curved toward each other in conformity with the arch of the top edge of the back, the extensions being corner welded to this edge and their end edges being welded to each other, thus forming an arched top for the box. On the ends of the wings 9 are lips 12, which are bent along three vertical lines, 13, 14, 15 in such manner as to form a vertical door-post portion 16 bent inward at right angles to each side, parallel with the back, a door-jamb portion 17 bent backward into the interior of the box, and a door-stop portion 18 bent transversely inward from the door-jamb.

In this way a Z-section door-frame structure in one piece with the side and back section is produced, and a high degree of stiffening with the least extra weight is obtained.

The back and sides are further formed with bottom flange lips 19, which are bent horizontally inward to support a horizontal bottom sheet 20, which is suitably secured

in place. On the forward edge of this sheet is a lip 12^a like the lips 12, which is bent on the three lines 13^a, 14^a, 15^a, to form a bottom Z-section door-frame structure, the ends of which are welded to the lower ends of the side members of the door-frame.

The top of the door-frame is formed by a top front section, which is best formed of three pieces, a center piece 21, and two side, 10 corner pieces 22. These pieces are formed up separately and welded together, and the section thus produced is then corner welded to the front edge of the top and welded also to the side door-frame members. The pieces 15 are cut with curved upper edges to correspond with the curvature of the top; the lower edge of the piece 21 is horizontal and the lower edges of the pieces 22 are inclined to correspond to the usual shape of 20 the top of the doors 23. These lower edges are each bent twice on the lines 14^b, 15^b first backward into the interior of the box and then downward, to complete the door-frame and stiffening structure at the top.

25 A pair of side-hinged doors 23 is shown, but a top hinged door may be used as well, the two forms of door being well-known.

A wooden lining 24 is constructed within the metal box to keep the contents from 30 rattling and striking sparks, and to afford desirable shelving and partitions. This lining is retained at the front within the door-framing, as is seen in Figs. 3 and 4.

The back section is cut with a large opening 25 conforming substantially to the outline of the tank extension 5, but of slightly 35 smaller diameter, so that the edge of the opening projects inward past the edge of the extension, the sheet thus abutting the extension. Pairs of parallel slits are cut in the edge of the opening, and the metal between these slits is bent rearward of the box (that is to say forward of the tank), forming lugs 26 which extend within the extension 5 and lie against the inner face thereof. The ends of these lugs are then welded to 40 said face of the extension as indicated at 27. The contraction of cooling draws the back section close against the extension; and to complete a perfectly tight smooth joint 45 the corner between the box back and the extension is soldered along the upper half. Since the welds 27 occur only at intervals 50 they may be partly superposed on the weld 4 of the tank head, as shown in Fig. 5, without interfering with access to this main weld in case of necessity, and the extension 5 can be of minimum length.

The particular form of bucket-box just 60 described is one which projects beyond the perimeter of the tank at the upper part as well as at the sides and bottom. In another form, the box conforms with the tank substantially over the upper half, and in such case the opening of the back sheet is not

entirely within the edges, but is represented by a deep arc.

With this construction it is more convenient to make the back section 7^a of two pieces which are welded together at their inner 70 ends, below the opening or cut-outs, the construction being otherwise like that previously described, except that over the upper half the box is but-welded to the end of the tank. 75

The removal of a large or major part of the area of the back section, leaving practically only a frame, reduces to a substantial extent the amount of dead weight that must be carried, in itself an important consideration, but does not weaken the structure of the box, which is so stiffened, strengthened and inherently braced by the welding to the tank and by the manner in which its members are formed and co-operatively related, that the structure is amply capable of withstanding the racking strains to which it is subjected at the rear end of the tank truck. 80 85

The conditions affecting one of these 90 bucket boxes are of a severe and peculiar character, and the purpose governing the construction of the several parts and the fabric as a whole is not only to provide a suitable enclosure, but also to obtain, without undue weight, a high degree of resistance to disintegrating forces which act upon a naturally vulnerable part of the body of a heavy and heavily loaded vehicle, which travels rapidly over roadways of all characters. 95 100

The advantages of the present bucket-box result from a number of features. Instead of making the box of a shell and two heads welded to the edges of the shell, as in the 105 Davis Patent 1,248,088, the back sheet section is in one piece with the sides and the top; furthermore, the side members of the door-frame are formed by repeated bendings from these side wall portions, greatly 110 stiffening the structure and further avoiding welding at the vertical corner edges. It may be noted that this is true of the form shown in Fig. 9, as well as in the form of 115 Figs. 1 to 8, for while in Fig. 9 the back sheet section is shown made for convenience from two pieces welded together at the middle of the back, the effect is the same as if one single piece were employed, the sides and top and the side door frame members 120 being all made continuous with each other and with the back, by bending, and the dihedral angles at 11, 13, 14 and 15 being bends and not welds. In like manner, the Z section bottom part of the door-frame and door stop is formed integral, by bending, with the bottom sheet, which in turn rests upon flanges 19 integrally bent from the main unit. The top front section also has 125 integrally bent flanges completing the door 130

frame and stop, and when formed, as in Fig. 7, of three pieces, permits of an arched top line of the box being combined with a polygonal top line of the door and door opening, in a very rigid construction.

It will thus be perceived that the invention involves a manner of construction and assemblage of forms and pieces, and a combination of bending and welding, to secure great strength in the box and advantage in manufacture; and likewise an improved manner of uniting the back of the box to the end of the tank.

What is claimed as new is:

15. 1. In a road vehicle tank, a welded bucket-box, having a main part formed of a back sheet section with end wings bent forward therefrom to form the sides of the box, said wings having upward extensions which are curved toward each other and united to form an arched top for the box, said back sheet section welded to the end of a tank, and other parts welded to said main part and completing the box structure.
20. 2. A welded bucket-box for vehicle tanks, having a back sheet section with end wings bent forward therefrom to form the sides of the box, said wings having upward extensions which are curved toward each other and united to form an arched top for the box, all the foregoing being formed of one continuous sheet, a top front section having an arched upper edge welded to the front edge of said arched top.
25. 3. A welded bucket-box for a road tank vehicle, having a main part comprising a back sheet section with end wings bent forward therefrom to form the sides of the box, said wings having side door-frame structures bent from their forward edges and upward extensions which are curved toward each other and united to form an arched top for the box, together with other angularly bent pieces welded to said main part and completing the box and door-frame structure.
30. 4. A welded bucket-box for vehicle tanks, having a back sheet section with end wings bent forward therefrom to form the sides of the box, said wings having side door-frame structures bent from their forward edges and upward extensions which are curved toward each other and united to form an arched top for the box, all of the foregoing formed of one continuous sheet, a top front section having an arched upper edge joined to the front edge of the top and a flanged door-frame element bent from its lower edge.
35. 5. A welded bucket-box for vehicle tanks, having a back sheet section with end wings bent forward therefrom to form the sides of the box, said wings having side door-frame structures bent from their forward edges and upward extensions which are curved toward each other and united to form an arched top for the box, the arched top front section composed of a center piece and two side pieces, welded together and to the edge of the top and having a horizontal and two inclined door-frame elements bent from their lower edges.
40. 6. A welded bucket-box for vehicle tanks, having a back sheet section with end wings bent forward therefrom to form the sides of the box, said wings having side door-frame structures bent from their forward edges and upward extensions which are curved toward each other and united to form an arched top for the box, and a top front section composed of a center piece and two side pieces welded together and to the edge of the top and having a horizontal and two inclined door-frame elements bent from their lower edges, and a section forming the bottom of the box, having a bottom door frame structure bent from its forward edge.
45. 7. A welded bucket-box for a road tank vehicle, having a back sheet section with end wings bent forward therefrom to form the sides of the box, said wings having upward extensions which are curved toward each other and united to form an arched top for the box, said section being further formed with inturned bottom flanges, and a bottom sheet supported on said flanges.
50. 8. A welded bucket-box for vehicle tanks, having a back sheet section which is welded to a tank with end wings bent forward from said back section to form the sides of the box, and Z-section side door-frame structures bent from the forward edges of said wings, all formed of one continuous sheet of metal.
55. 9. A welded bucket-box for vehicle tanks, the arched top front section composed of a center piece and two side pieces, welded together and

curved toward each other and united to form an arched top for the box, a top front section having an arched upper edge joined to the front edge of the top and a flanged door-frame element bent from its lower edge, and a bottom section having a bottom door-frame structure bent therefrom.

10. A welded bucket-box for vehicle tanks, having a back sheet section with end wings bent forward therefrom to form the sides of the box, said wings having upward extensions which are curved toward each other and united to form an arched top for the box, and a top front section having an arched upper edge welded to the front edge of said arched top, and a bottom section welded in the bottom of the box.

11. A welded bucket-box for vehicle tanks, having a back sheet section with end wings bent forward therefrom to form the sides of the box, said wings having side door-frame structures bent from their forward edges and upward extensions which are curved toward each other and united to form an arched top for the box, and a top front section composed of a center piece and two side pieces welded together and to the edge of the top and having a horizontal and two inclined door-frame elements bent from their lower edges.

12. A welded bucket-box for vehicle tanks, having a back sheet section with end wings bent forward therefrom to form the sides of the box, said wings having side door-frame structures bent from their forward edges and upward extensions which are curved toward each other and united to form an arched top for the box, and a top front section composed of a center piece and two side pieces welded together and to the edge of the top and having a horizontal and two inclined door-frame elements bent from their lower edges, and a section forming the bottom of the box, having a bottom door frame structure bent from its forward edge.

13. A welded bucket-box for a road tank vehicle, having a back sheet section with end wings bent forward therefrom to form the sides of the box, said wings having upward extensions which are curved toward each other and united to form an arched top for the box, said section being further formed with inturned bottom flanges, and a bottom sheet supported on said flanges.

14. A welded bucket-box for vehicle tanks, having a back sheet section which is welded to a tank with end wings bent forward from said back section to form the sides of the box, and Z-section side door-frame structures bent from the forward edges of said wings, all formed of one continuous sheet of metal.

15. In a welded bucket-box, the arched top front section composed of a center piece and two side pieces, welded together and

having a horizontal and two inclined flanged door-frame elements bent from their respective lower edges.

12. A welded sheet-metal bucket-box for vehicle tanks having a back welded to the end of a tank, sides formed with Z section door-frame structures bent from their forward edges, a top, and a top front section welded to the top and sides and bent so as to also form a Z section door-frame structure, said door-frame structures being in one piece with the parts from which they are bent and terminating in free flanges.
13. A welded sheet-metal bucket-box for vehicle tanks having a back welded to the end of a tank, sides formed with Z section door-frame structures bent from their forward edges, a top, a top front section welded to the top and sides and bent so as to also form a Z section door frame structure, and a section forming the bottom of the box having a similar door-frame structure bent from its forward edge.
14. In a welded vehicle tank, the combination with a horizontal tank, having a rearward peripheral extension, of a bucket-box having a back sheet, having its interior cut out and lugs bent from its inner edge within the rearward extension of the tank and welded thereto.
15. In a welded vehicle tank, the combination with a horizontal tank, having a rearward peripheral extension, of a bucket-box having a back sheet, abutting said extension, said sheet having its interior cut out to form an opening edge of which extends inwardly of the wall of the tank extension, said edge being cut and having lugs bent therefrom to lie against the inner face of the tank extension, and welds uniting the lugs to the inner face of said extension.
16. A welded bucket-box for a road tank vehicle, having a back sheet section which

is welded to a tank, wings bent forward therefrom to form the sides of the box, and 45 lips on the forward edges of said sides bent into door-frame members, all formed of one continuous sheet of metal.

17. A welded bucket-box for a road tank vehicle, having a back sheet section which is 50 welded to a tank, wings bent forward therefrom to form the sides of the box, and lips bent inward toward each other from the forward edges of said sides and further bent rearward and then again inward to form a 55 jamb and door-stop, all formed of one continuous sheet of metal.

18. A bucket-box for a road tank vehicle having a main part comprising a back sheet section with end wings bent therefrom to 60 form the sides of the box and extensions from the tops of said end wings welded together and forming the top of the box, and with side door-frame members bent from the forward portions of said sides in a succession of dihedral angles, together with other pieces welded to said main part and completing the structure of the bucket-box and its stiffening door-frame.

19. A bucket-box for vehicle tanks having 70 a main part comprising a back sheet section with end wings bent therefrom to form the sides of the box and extensions from the tops of said end wings welded together and forming the top of the box, and with side door 75 frame members bent from the forward portions of said sides in a succession of dihedral angles, together with other pieces welded to said main part and completing the structure of the bucket-box and its stiffening door-frame, said back sheet section being formed with an interior opening corresponding approximately to the end of a tank to which said back sheet is welded.

ARTHUR L. BETTS.
ANTHONY B. FEY.
